ELECTRIC SWITCH

Filed July 28, 1928

UNITED STATES PATENT OFFICE

GEORGE A. BURNHAM, OF SAUGUS, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

ELECTRIC SWITCH

Application filed July 28, 1928. Serial No. 295,905.

This invention relates to electric switches or circuit breakers and has particular reference to the stationary and movable arcing contact members which cooperate to interrupt the current flowing through the circuit.

Various devices have been employed to assist in extinguishing the circuit interrupting arc drawn between the separating contact members, but most circuit breakers depend primarily upon the quick separation of the contact members themselves, whereby the arc is rapidly attenuated and becomes so unstable that it goes out. Particularly in oil immersed circuit breakers, it is considered imperative that the arc be extinguished as quickly as possible since its presence in the oil causes rapid decomposition thereof into inflammable gases and vapors. Consequently it is the practice to operate the movable switch member with great rapidity either by gravity and inherent resilience of the contacts or by powerful accelerating springs associated with the operating mechanism. Particularly in the latter case, some means must be provided to absorb the energy of the movable switch member at the end of its opening stroke, and to this end resilient bumpers have been provided for the switch member, or decelerating springs have been placed in the operating mechanism. The former remedy is objectionable due to the rebound which tends to cause the re-establishment of the arc, while the latter has a tendency to retard the switch member before the arc has been extinguished.

A circuit breaker is sometimes called upon to interrupt a current many times its normal rating, due to a short circuit or some other severe overload condition, and the arc between the contacts may persist and cause the destruction of the contacts. Particularly in the case of oil immersed circuit breakers the damage may be very great due to the generation of inflammable oil gases and vapors, and a destructive explosion may result from a persistence of the arc after the contacts are fully separated.

It is an object of the present invention to

provide a circuit breaker wherein the separable contacts are separated, preferably at the latter part of the switch opening movement, and when the arc is already attenuated and unstable, at a speed which is higher than that of, and is due to, the speed of the movable switch member, thus to extinguish an arc which might otherwise persist for a substantial period of time.

It is a further object of the invention to provide means for utilizing the surplus energy of the movable switch member at the end of its switch opening movement to enhance the extinguishment of the circuit interrupting arc, and specifically to utilize the energy of the movable switch member to effect a further rapid separation of the arcing contact members through the oil during the final opening movement of the switch.

It is another object of the present invention to provide an improved construction for a quick-opening circuit breaker wherein the dynamic energy of the movable switch member is absorbed at the end of its stroke without appreciable rebound.

A still further object is generally to improve the construction and performance of electric circuit breakers.

Fig. 1 is a sectional elevation of an oil immersed electric switch or circuit breaker embodying the invention.

Fig. 2 is a sectional elevation of the switch taken on lines 2—2 of Fig. 1.

Fig. 3 is a perspective view of the supporting bracket for the movable arcing contact members.

Fig. 4 is a perspective view of a contact supporting arm for an arcing contact member.

Fig. 5 is a detail showing the spring associated with the contact arm of Fig. 4 and the supporting bracket of Fig. 3.

As herein shown, the electric switch embodying the invention includes a switch frame 10 adapted to provide a cover for the depending rectangular receptacle 12 which contains a body of arc quenching fluid as oil in which the cooperating stationary and mov-

able contact members of the switch are immersed.

Stationary switch members are supported by said switch frame 10 and depend therebelow into the oil in said receptacle 12 and include the porcelain insulating bushings 14 which enclose axial conducting studs 16. Said studs extend beyond the lower ends of said bushings and are screw-threaded at their lower extended ends into the stationary main contact members or blocks 18.

Stationary auxiliary contacts or arcing members 19 are provided adjacent said main contact blocks and are secured in conducting relation with said block and held fixedly in position thereagainst by means of screws 19a.

The movable switch member includes the insulating switch operating rod 20 which is adapted to carry the main and auxiliary movable contact members at its lower end in position to engage the stationary main and auxiliary contact members 18 and 19 and complete the circuit through the switch. A metal rod 22, secured to said insulating rod 20 at its upper end, is operatively connected to suitable switch operating mechanism (not shown). At its lower end said rod 20 is provided with an enlarged portion 23, preferably of metal, to which the main movable brush member 24 is removably secured by means of a U-shaped metal clamp 25 having the upstanding ends 26 which are adapted to closely receive the laminations of the movable contact, or brush, 24 therebetween. A pin 30 extends through the upstanding ends 26 of said U-shaped clamp and the enlarged portion 23 of said switch operating member whereby said brush is removably secured to said operating rod 20, and fasteners 32 serve to secure the laminations of the brush or bridging member 24 to the bottom of said U-shaped clamp 25.

The U-shaped clamp 25 is further provided with opposed outwardly and downwardly extended arms, or brackets, 34, Fig. 3, which are arranged to support the movable auxiliary contact or arcing members therebeneath. To this end said arms 34 are each provided with a pair of spaced depending ears 36 at their free outer ends upon which contact supporting rocker arms 38 of the auxiliary contact members are pivotally supported by pins 40. As shown in detail in Fig. 4, said contact supporting arms 38 are of channel section and are provided with supporting ears 42 intermediate their ends by which they are pivotally supported on the pins 40 between the ears 36 of said brackets 34. Contact or arcing members 44 are secured detachably by screws 47 to the outwardly directed upturned ends 48 of said supporting arms 38 in position to cooperate with the stationary contacts 19.

Said arms 38 are further provided with integral inwardly extended arms 50 the up-

turned ends of which are disposed side by side or overlap each other at a point beneath the middle of said U-shaped clamp 25. Said arms 50 preferably have struck out portions 51 at their overlapping ends as shown in Figs. 2 and 4, so that both arms are free for vertical movement without interference from the other.

Means are provided constantly to bias said contact supporting arms 38 in an upward direction against the ends 52 of the brackets 34, which act as abutments to limit the upward movement of the arcing contact members. Said means comprise the constantly stressed cantilever springs 54 which encircle the pins 40, one end of each spring passing through said pins 40 and the other end extending beneath and bearing against an arm 38, as shown in Fig. 5. The movable arcing contact members 44 are consequently urged against their cooperating contacts 19 when the switch is in closed position, and due to the above resilient support are caused to remain in contact therewith for a sufficient time subsequent to the separation of the main brush member 24 to prevent arcing at the main contacts and brush members.

When the operating rod 20 is moved downwardly to open the switch, an arc is drawn between each pair of auxiliary contact members 19 and 44 and it attenuated by the downward movement of the movable switch member, the opening speed of which is enhanced by an accelerating spring 45, surrounding the rod 22. Under normal conditions the arc will become unstable and go out before the movable switch member has reached the end of its opening stroke, but under heavy overload conditions the arc between the auxiliary contacts 19 and 44 may persist after the movable switch member has reached the end of its opening stroke and may, unless extinguished, cause the destruction of the switch.

According to the invention, means are provided to effect, during the final opening movement of the switch member, an extent of separation of the arcing members which is greater than the stroke of the movable switch member, and a speed of separation which is materially greater than the speed of opening movement of the movable switch member. To this end a resilient bumper is provided directly beneath and in axial alignment with said movable operating rod 20, which bumper is arranged to engage the tips of the inwardly directed overlapping arms 50 of said contact supporting arms 38 prior to the end of the opening stroke of the movable switch member. Said bumper as here shown includes a piston 56 having an upstanding stem 58 which is axially aligned with the operating rod 20 and hence directly beneath the adjacent struck-out ends of arms 50, an enclosing casing 60 for said piston, and a helical compression spring 62 disposed within said

casing beneath said piston and in position constantly to bias said piston in an upward direction. Said casing is suitably supported in fixed position as by being secured by bolts 64 to and beneath a cross bar 66 which extends across the centre of the switch casing 12 perpendicular to the bridging member 24. Uprights 68 preferably of insulating material extend upwardly from said cross-bar in position to be secured removably by bolts 70 to a pair of suitably spaced depending ears 72 which may be formed integral with the switch frame 10.

As the movable switch member nears the end of its switch opening movement, the arms 50 engage the stem 58, and since the spring 62 beneath the piston 56 is relatively stiff compared with the springs 54 of the auxiliary contact members, the springs 54 yield the most and cause the contact supporting arms 38 to rotate about pins 40 to effect a further and rapid separation of the arcing contacts towards the lower dotted line position of Fig. 1. The spring 62 is initially compressed upon the engagement of the stem 68 and arms 50 and absorbs enough of the energy of the switch opening movement to prevent injury to the mechanism, and reacts immediately to continue the downward and outward movement of the movable arcing tips 44.

It will be noted that during the opening movement of the switch into the intermediate dotted position of Fig. 1, prior to the engagement of the stem 58 with the arms 50, the arcing members 44 are moved in a uniform vertical path away from their cooperating contacts 19, while the subsequent movement of the contacts 44 due to the pivotal movement of arms 38 about their supporting pins 40, is at an angle to this path and to the axis of the existing arc. The location of the pivot points of the contact supporting members 38 is such that a small linear movement of the arms 50 causes a considerably greater linear movement of the outer arms 48 on which the arcing contact members are carried; so that the rapid movement of the movable switch member against the bumper, due to the accelerating spring and the force of gravity, causes the arcing tips to be moved downwardly through the oil suddenly and at an angle to the axis of the existing arc into the lower dotted position of Fig. 1, and any arc which may have persisted will be caused to go out, the arcing member 44 being snapped away from the foot of the arc as well as being laterally displaced therefrom in the oil.

The work performed in moving the contact bearing arms 38 suddenly through the oil against the bias of springs 54 is considerable and consequently the force of the movable switch member is dissipated without any appreciable reaction. The spring 62 beneath the piston serves largely to protect the movable

switch member from the initial impact against the stem 58 and being relatively rigid will react before the end of the switch opening stroke of the switch member.

The uprights 68 which support the bumper are arranged to be vertically adjustable to vary the point in the switch opening movement at which the bumper will operate to snap the arcing contacts apart. To this end a series of vertically aligned holes 74 are provided in the uprights 68 through any of which the bolt 70 may be inserted.

Although I have disclosed the invention as embodied in an oil immersed electric switch it is equally applicable to air-break switches and various modifications in the structure may be made without departing from the scope of this invention.

I claim:

1. In an electric switch, the combination of a stationary switch member, a movable switch member having an arcing member which is movable therewith and which cooperates with said stationary switch member, and means effective only during the later part of the opening movement of the movable switch member and after said arcing member has been moved at the velocity of opening movement of said movable switch member a substantial distance out of engagement with said stationary switch member to move said arcing member further in a direction away from said stationary switch member at a rate of speed which is greater than the opening speed of said arcing member due to the speed of said movable switch member.

2. The method of interrupting an electric arc which consists in initially elongating it at a suitable rate and then in suddenly elongating it at a materially increased rate.

3. The method of interrupting an electric arc which consists in elongating it at a suitable rate until it becomes unstable and thereupon continuing its elongation at a materially increased rate.

4. In an electric switch, the combination of a stationary switch member, a movable switch member, a pivotally mounted arcing member carried by the movable switch member and engageable and disengageable with said stationary switch member, and means cooperating with said movable switch member and effective only after the arcing member has moved a substantial distance away from said stationary switch member to rotate said arcing member about its pivot in a switch opening direction during and by the switch opening movement of the switch.

5. In an electric switch, the combination of a pair of stationary switch members, a movable switch member, a pair of pivotally mounted arcing members carried by the movable switch member and movable at the switch opening speed thereof out of engagement with and into a position remote from

5 said stationary switch member, and means co-operating with said movable switch member near the end of its switch opening movement constructed and arranged to engage said movable switch member and rotate said arcing members about their pivots in a switch opening direction during the final switch opening movement of said movable switch member and at a speed greater than the speed of said 10 arcing members due to the opening speed of said movable switch member.

6. In an electric switch, the combination of a switch member which is movable between switch open and closed positions, a stationary 15 switch member, an arcing member pivotally carried by said movable switch member, and means operated by the opening movement of said movable switch member to engage and move said arcing member about its pivot in a 20 switch opening direction only during the final part of the switch opening movement.

7. In an electric switch, the combination of a movable contact member, a stationary contact member, an auxiliary contact supporting arm carried by said movable contact member and movable in respect thereto, an arcing member carried by said arm, and means normally operatively free from but engageable with said arm during the final part only of the 25 opening movement of said movable contact member to move said arcing member in a switch opening direction and at a speed in excess of the speed of said arcing member due to the opening speed of said movable contact member.

8. In an electric switch, a stationary switch member, a cooperating movable switch member, means to separate said members at a given rate, and other means operative after 30 said members have been separated a given distance to increase the rate of separation of said switch members.

9. In an electric switch, a stationary switch member, a cooperating movable switch member having a pivotally supported arcing tip movable between switch open and closed positions, and means disposed in the switch opening path of movement of said movable switch member and normally operatively free 45 from said switch member arranged to engage and rotate said moving arcing tip about its pivotal support in a switch opening direction only after said arcing tip has moved a given distance.

50 10. In an electric switch, a stationary switch member, a cooperating movable switch member, an arcing contact member having a movable support on said movable switch member and movable therewith into and out 55 of switch closing position, and a relatively fixed abutment normally operatively free from and disposed in the switch opening path of movement of said movable switch member in position to engage and move said arcing 60 contact member about its movable support

in a switch opening direction during the final part of movement only of said movable switch member.

11. In an electric switch, a movable switch member including a switch operating rod, and a pivoted contact member movable therewith into and out of switch closing position, and a resilient bumper disposed beneath said movable switch member in position to engage said contact member and rotate it about its pivotal support in a switch opening direction during the movement of said switch member into switch open position.

12. In an electric switch, the combination of a movable switch member including a reciprocal switch operating rod, a main contact member disposed at the lower end of said rod, a downwardly and outwardly extended bracket carried by the lower end of said rod, a contact supporting member pivoted to the extended end of said bracket and having a relatively long contact supporting arm and a short striker arm, an arcing tip carried at the extended end of said contact supporting member, and a relatively fixed abutment disposed beneath said movable switch member in position to engage said striker arm at the end of the switch opening movement of said movable switch member.

13. In an electric switch, the combination of a movable switch member including a reciprocal switch operating rod, a main contact member disposed at the lower end of said rod, a downwardly and outwardly extended bracket carried by the lower end of said rod, a contact supporting member pivoted to the extended end of said bracket and having a relatively long contact supporting arm and a short striker arm, an arcing tip carried at the extended end of said contact supporting member, and a relatively fixed abutment disposed beneath said movable switch member in position to engage said striker arm at the end of the switch opening movement of said movable switch member.

14. In an electric switch, the combination of a pair of spaced stationary switch members, a movable switch member cooperating therewith, a pair of pivotally mounted arcing contact members carried by said movable switch member, and means to prevent a rebound of said movable switch member at the end of its switch opening movement including a resilient abutment disposed in the path of movement thereof and in position to engage and move said arcing contact members rapidly about their pivotal support in a switch opening direction, whereby to absorb the energy of switch opening movement of said movable switch member.

15. The method of interrupting an electric

circuit which consists in drawing an arc, attenuating the arc until the arc reaches a stage where it becomes unstable, and causing the arc to go out by suddenly increasing the rate of attenuation of the arc.

5 16. The method of interrupting an electric circuit which consists in drawing an arc between two cooperating contact members, separating said contact members substantially in a straight line to attenuate the arc and cause it to become unstable, and subsequently causing one of said contacts to move suddenly further away from its cooperating contact member and at an angle to the previous line of separating movement thereof.

10 17. The method of interrupting an electric circuit which consists in establishing an arc in an arc quenching fluid, attenuating said arc slowly in a uniform path until said arc becomes unstable, and then rapidly attenuating said arc and simultaneously displacing it laterally of said path in the arc quenching fluid.

15 18. The method of interrupting an electric switch which consists in establishing an arc between two cooperating arcing contact members and beneath an arc quenching fluid, drawing the arc out by separating said contact members in a uniform path, and finally moving one of said contact members with a snap action at an angle to said first path of movement, whereby to further attenuate the arc and also to snap said contact member laterally away from the foot of the arc.

20 19. The method of operating an electric switch of the type having a movable switch member and an arcing member movable on said switch member, which consists in arresting the opening movement of the movable switch member in the latter part only of its switch opening movement and utilizing the energy thereof in moving the arcing member in a switch opening direction.

25 20. In an electric switch, engageable and disengageable contact members, and means to separate the disengaged contact members at a given rate including means effective only after a given extent of separation to suddenly increase the rate of separation of said contact members.

30 In testimony whereof, I have signed my name to this specification.

GEORGE A. BURNHAM.
